(57) **CLAIM**

The ornamental design for a front bumper side grille for a vehicle, as shown and described.

DESCRIPTION

FIG. 1 is a front left perspective view of a front bumper side grille for a vehicle according to the present invention.

FIG. 2 is a front right perspective view of the front bumper side grille shown in FIG. 1.

FIG. 3 is a rear right perspective view thereof.

FIG. 4 is a rear left perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is a front view of the front bumper side grille shown in FIGS. 1-10, but with the front bumper side grille mounted on a vehicle, and the rest of the vehicle shown in de-emphasized and half-tone portions so as to illustrate environmental structure. These portions form no part of the claimed invention. More particularly, in FIG. 11, the inventive front bumper side grille is shown within the outer broken line, and the elements shown outside the outer broken line form no part of the claimed invention. Nonetheless, the inner broken lines located inside the outer broken line form no part of the claimed design. Also, the invention contemplates a mirror image front bumper side grille on the opposite side of the vehicle.
